(57) **CLAIM**

The ornamental design for a mop handle, as shown and described.

DESCRIPTION

FIG. 1 is a front perspective view of a mop handle showing the new design.

FIG. 2 is a rear elevational view thereof.

FIG. 3 is a front elevational view thereof.

FIG. 4 is a right side elevational view thereof. The left side elevational view is a mirror image of the right side elevational view.

FIG. 5 is a bottom view thereof; and,

FIG. 6 is a top view thereof.

The broken line showing is included for the purpose of illustrating portions of the mop handle and forms no part of the claimed design.

1 Claim, 5 Drawing Sheets*FIG. 1*

FIG. 2

FIG. 3

FIG. 4

FIG. 5

FIG. 6
